UNITED STATES PATENT OFFICE

ELTON ADAMS, OF DRYVILLE, PENNSYLVANIA

TANK LOCK

Application filed June 11, 1930. Serial No. 460,441.

The present invention relates to a lock for fuel tanks on automobiles and the like and has for its prime object to provide means for locking the cap on the filling neck of the tank so as to prevent the theft of fuel therefrom.

Another very important object of the invention resides in the provision of a gasoline tank lock of this nature which is exceedingly simple in its construction, strong and durable, easy to manipulate with the authorized key, thoroughly efficient and reliable in use and operation, compact and convenient in its arrangement of parts, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a fragmentary top plan view of a tank with my improved locking structure incorporated therein,

Figure 2 is a vertical section therethrough taken substantially on the line 2—2 of Figure 1,

Figure 3 is a horizontal section taken substantially on the line 3—3 of Figure 2,

Figure 4 is another horizontal section taken substantially on the line 4—4 of Figure 2,

Figure 5 is a perspective view of the lock barrel,

Figure 6 is a perspective view of the key.

Figure 7 is a perspective view of one of the links and its locking rod, and

Figure 8 is a perspective view of the rockable disk with its pair of arms.

Referring to the drawings in detail it will be seen that the numeral 5 denotes a neck rising from the tank 6. On the upper edge of the neck 5 there are formed a pair of inwardly disposed downturned arcuate flanges 7 having stops 8 formed at the ends thereof, one on each flange, the stops being disposed in diametric relationship to each other. The numeral 9 denotes a cap having a depending peripheral annular skirt 10. The center of

the cap is formed with a depending sleeve 12 to receive a lock structure 14 of conventional construction except that it is somewhat more elongated than is usual and intermediate its ends is provided with a groove 15 to receive a locking ring 16 for abutting the lower end of the sleeve 12 for the purpose of holding the locking structure in place.

A plate 17 is disposed under the cap 9 circumjacent the sleeve 12 and has diametrically disposed outwardly directed extensions 18 terminating in depending ends 19 which merge into outwardly directed lugs 20 to engage under the bottom edges of the flanges 7. A cup 21 is disposed under the cap 9. The cap 9, extensions 18 and the cup 21 are anchored together by means of screws 22 or in any other preferred manner.

On the bottom of the cup 21 there is a rockable disk 23, the center of which has a trunnion 24 journaled in an opening in the center of the bottom of the cup 21. Diametrically disposed outwardly extending arms 25 are formed on the disk 23. The disk 23 is provided with depressions 26 to receive prongs 27 on the end of a key 28 insertable into the lock structure 14 so that when the key is inserted in the lock structure with the prongs 27 engaged with the depressions 26 said disk 23 may be turned by turning the key 28.

Links 30 are pivotally engaged on the ends of the arms 25 and have downwardly offset extremities 31 in which are fixed inner ends of locking rods 32 which are slidable through openings 33 in the top 21.

The outer extremities of these locking rods are adapted to be projected into an annular groove 34 formed in the interior of the neck 5 and when thus projected prevent the removal of the cap 9 as will be quite apparent. In order to remove the cap 9 a key is inserted in the lock structure and turned to release the locking rod 32 from the groove 34 and then the cap may be turned to free the lugs 20 from the flanges 7 and the cap removed with ease. To lock the cap in place, of course, the above operation is reversed.

It is thought that the construction, operation, utility and advantages of this inven-

tion will now be quite apparent to those skilled in this art without a more detailed description thereof.

The present embodiment of the invention **5** has been described in considerable detail merely for the purposes of exemplification since in actual practice it attains the features of advantage enumerated as desirable in the statement of the invention and the **10** above description.

It will be apparent that changes in the details of construction, and in the combination and arrangement of parts may be resorted to without departing from the spirit **15** or scope of the invention as hereinafter claimed or sacrificing any of its advantages.

Having thus described my invention, what I claim as new is:

In combination with a tank having a neck **20** and a cap for closing the neck, said neck having an internal groove therein, a cup-shaped member connected with the bottom face of the cap and extending into the neck, an arm carrying member pivotally connect-
25 ed with the upper face of the bottom of the cup, locking members connected with opposing ends of said member and having their outer ends adapted to engage the groove in the neck when said member is turned in **30** one direction, said cup having holes therein through which the locking members pass, a key-receiving lock carried by the cap and having its lower end located above the pivoted member, said pivotal member having **35** depressions forming shoulders therein adapted to be engaged by a key to project or retract the locking members into and out of the groove.

In testimony whereof I affix my signature.
